United States Patent [19]

Collins et al.

[11] Patent Number: Des. 304,339

[45] Date of Patent: ** Oct. 31, 1989

[54] TELEPHONE NETWORK INTERFACE APPARATUS

[75] Inventors: Thomas J. Collins, Wall; Pina Schneider, Ocean Township; Anthony L. Nieves, Bradley Beach; Thomas G. Graham, Ocean, all of N.J.

[73] Assignee: Keptel, Inc., Tinton Falls, N.J.

[**] Term: 14 Years

[21] Appl. No.: 139,427

[22] Filed: Dec. 30, 1987

CLAIM

The ornamental design for telephone network interface apparatus, as shown and described.

DESCRIPTION

FIG. 1 is a front elevational view of a telephone network interface apparatus showing our new design in closed position;

FIG. 2 is a rear elevational view thereof; FIGS. 3 and 4 are respectively top and bottom plan view thereof; FIGS. 5 and 6 are respectively right and left side elevational views thereof; FIG. 7 is a front, top and right side perspective view thereof; FIG. 8 is a front and top perspective view of the apparatus in partially opened position; and FIG. 9 is a front elevational view showing the apparatus in fully opened position.

FIG.1

FIG. 2

FIG. 3

FIG. 4

FIG.5

FIG.6

FIG. 7

FIG. 8

FIG. 9
